(57) CLAIM

The ornamental design for a bath pillow, as shown and described.

DESCRIPTION

FIG. 1 is a top, front, left side perspective view of a first embodiment of the bath pillow;

FIG. 2 is a front elevational view of the bath pillow shown in FIG. 1;

FIG. 3 is a rear elevational view of the bath pillow shown in FIG. 1;

FIG. 4 is a top plan view of the bath pillow shown in FIG. 1;

FIG. 5 is a bottom plan view of the bath pillow shown in FIG. 1; and

FIG. 6 is a left side elevational view of the bath pillow shown in FIG. 1, the right side being a mirror image thereof.

FIG. 7 is a top, front, left side perspective view of a second embodiment of the bath pillow;

FIG. 8 is a front elevational view of the bath pillow shown in FIG. 7;

FIG. 9 is a rear elevational view of the bath pillow shown in FIG. 7;

FIG. 10 is a top plan view of the bath pillow shown in FIG. 7;

FIG. 11 is a bottom plan view of the bath pillow shown in FIG. 7; and,

FIG. 12 is a left side elevational view of the bath pillow shown in FIG. 7, the right side being a mirror image thereof.

Any portions shown in dashed or broken lines are included for illustrative purposes only and form no part of the claimed design.
